(57) CLAIM

The ornamental design for a patio grill, as shown and described herein.

DESCRIPTION

FIG. 1 is a left front perspective view of the patio grill of the invention.

FIG. 2 is a frontal elevational view of the patio grill of the invention.

FIG. 3 is a rear elevational view of the patio grill of the invention.

FIG. 4 is a right side elevational view of the patio grill of the invention.

FIG. 5 is a left side elevational view of the patio grill of the invention.

FIG. 6 is a superior view of the patio grill of the invention; and,

FIG. 7 is a bottom view of the patio grill of the invention. The broken lines in the figures depict portions of the patio grill that form no part of the claimed design.
